DISPLAY-FIXTURE.

Specification of Letters Patent.

Patented Aug. 9, 1921.

Application filed March 1, 1920. Serial No. 362,466.

To all whom it may concern:

Be it known that I, GERTRUDE M. MORRILL, a citizen of the United States, and a resident of the city and county of San Francisco, 5 State of California, have invented a certain new and useful Display-Fixture, of which the following is a specification.

The invention relates to display fixtures and particularly to fixtures for displaying a 10 hair dress.

An object of the invention is to provide a fixture for effectively displaying a style of hair dress.

The invention possesses other advantages, 15 some of which, with the foregoing, will be set forth in the following description where I shall outline in full, that form of the invention which I have selected for illustration in the drawings accompanying and forming part of the present specification.

In said drawings: Figure 1 is a front elevation of the display fixture of my invention. Fig. 2 is a side elevation of the 25 fixture.

Styles of hair dress have heretofore usually been displayed on heads of wax or plaster or comparable material, which displayed the entire hair dress. In accordance 30 with my invention I display a side elevation or profile of the hair dress on an attractive figure which lends grace and style to the hair dress.

The fixture of my invention comprises 35 a flat thin sheet 3 of material such as fiber board or other suitable material which is cut to produce the profile of the head and shoulders, and preferably also the arms of a woman. The surface of the sheet is properly tinted and delineated to present a pleasing profile and the sheet is secured to a suitable standard or post 4, which is secured to a base 5.

Secured to the sheet and overlying that portion of the head of the figure over which the hair is generally arranged is a quantity of hair 6, arranged and dressed in the fashion it is desired to display. The hair is dressed to display the profile effect of the head dress and when arranged, produces a very attractive figure. The hair is preferably arranged before it is attached to the sheet, to which it is secured by a suitable adhesive, but when desired, the hair may be permanently attached to the sheet and dressed on the figure. The hair dress stands out from the sheet and produces the effect of a full hair dress with the result that the display stand is effective and pleasing and lends itself readily to the attractive decoration of show windows.

I claim:

As an article of manufacture a hair dresser's advertising device consisting of a supporting member of thin sheet-like material simulating, in elevation the shoulders and arms of a woman's form having the head turned to full profile view so as to effectually display, in full profile, an applied suit of hair to attractively advertise hair dressing or transformations.

In testimony whereof, I have hereunto set my hand.

GERTRUDE M. MORRILL.
